DOUBLE-TWIST SPINDLE

Pierre de Halleux, Brussels, Belgium, assignor to
 Union des Fabriques Belges de Textiles Artificiels "Fabela," Societe Anonyme, Brussels,
 Belgium, a company

Application October 19, 1949, Serial No. 122,235
 In Belgium October 26, 1948

3 Claims. (Cl. 57—53)

1

This invention relates to hollow spindles which, by rotating at a high speed, give a double-twist to the yarn.

When the twisting of the yarn is effected with such spindles, either by winding the yarn or by reeling it off a bobbin which is kept stationary on the spindle, the yarn, under the action of the centrifugal force to which it is subjected, acquires a position of equilibrium and forms a "balloon" the diameter of which depends on the speed of rotation, on the thickness of the yarn, on the tension to which the yarn is subjected and on the distance between the point at which the yarn leaves the spindle and the fixed guide which is mounted in the axis of said spindle.

When the spindle is to be driven at high speed and when a fairly thick yarn, such as is obtained by assembling a plurality of single threads, is twisted, the balloon diameter rapidly becomes so large as to cause interference between the yarns of two adjacent spindles if the spacing between the latter is not increased, such an increase not always being possible to realize and which, in any case, involves an increase of the requisite floor-space of the machine. There have been attempts to prevent the yarns of neighbouring spindles from interfering with each other by positioning between the spindles so-called "anti-marriage" partitions, which partitions prevent the yarns of two adjacent spindles from getting accidentally entangled but they can not prevent an increase of the ballooning taking place due to some change in the twisting conditions, and it then happens that the yarn rubs against the surface of the partitions so that yarn breakages, which lower the quality of said yarn, occur.

In general, a control of the diameter of the balloon is effected by increasing the tension of the yarn by applying a braking action at a point positioned near the supply body, which tension must be increased with an increase in yarn thickness. In this manner packages are obtained the hardness of which depends on the tension that is applied to the yarn. It also has been suggested to use a storing ring positioned at the exit end of the spindle on which ring the yarn is wound and from which it is unwound following instantaneous variations of the tension. However, this winding brings about an increase in the total tension exerted on the yarn.

Devices are known in which a split stirrup or fork rotating with the spindle keeps the yarn in a plane passing through the exit opening of the spindle and the upper fixed point but such devices can not limit the diameter of the balloon.

2

It has also been proposed to limit the diameter of the balloon by means of a split ring mounted on a conical top cover flaring outward from the exit hole of the spindle on which top cover the yarn can wind itself so that even if this winding is limited a small tension due to friction is created.

The present invention aims to remedy these drawbacks by limiting the diameter of the balloon without having to apply a braking action to the yarn delivered by the yarn supply body, to allow the spindle to be rotated at high speed irrespective of the weight of the supply body and also to obtain packages which can be adjusted to the desired hardness by means of devices known per se, said devices being independent of the twisting spindle.

With this object in view, the spindle of this invention is characterised by a continuous surface which is exterior to the yarn and which rotates concurrently with the spindle so as to guide the yarn from the exit opening of the spindle to a point near the stationary yarn guide mounted in the axis of the spindle.

25 In the practical realization of this invention, the guiding surface may consist of a flexible or rigid tube joined to the rotating spindle through which tube the yarn is threaded.

The accompanying drawing given by way of example illustrates various devices, by no means limitative, for realizing the invention.

Figure 1 is a schematic representation of a device constructed according to this invention.

Figure 2 represents a horizontal or inclined spindle.

Figs. 3 and 4 respectively are side sectional and detail views of another embodiment of the invention.

In Fig. 2 the bobbin 6 is mounted on a carrier 7 supported by the spindle 3; the rotation of said bobbin being independent of that of the spindle due to the presence of bearings 8. The carrier 7 is rendered stationary by means of a balance weight 9. The yarn 1 reeled-off the bobbin is guided by spindle-cap 10. It enters the bore of the spindle 3 and leaves it through a side opening 5. The yarn is then threaded into a flexible tube 11 (corresponding to the surface 2 of Figure 1) fixed at point 12 of the spindle 3 and at point 13 in a carrier rotating freely in the stationary yarn guide 4 in bearing 14. The rotation of the tube is balanced by the balance-weight 15—16.

Irrespective of the speed of rotation and the weight of the yarn, the position the yarn will

assume in the space is determined by the length given to the flexible tube.

Figures 3 and 4 illustrate the bobbin 6 mounted on a support 7 carried by the spindle 3, the former being independent of the movement of the latter by virtue of bearings 8. The support 7 is immobilized by balance-weight 9. The yarn 1 wound off the bobbin and guided by the spindle cap 10 enters the bore of the spindle 3 and leaves it through the side opening 5. It is then threaded into a rigid tube 17 (similar to the flexible tube 11 and corresponding to the surface 2 of Fig. 1) fixed inside a bowl 18 forming an integral part of the spindle 3; the yarn being thereby guided to the fixed 15 yarn guide 4.

No tensioning of the yarn is required in order to counterbalance the action of the centrifugal force. The device of the present invention affords a means to adjust, as desired, 20 the hardness of the end package through any known thread tensioning device located at some point along the course of the yarn guide fixed to the end package (not shown).

I claim:

1. A device for limiting the size of the balloon of yarn in double-twist spindles comprising, in combination, a substantially cup-shaped body member fixedly connected at one end thereof to the spindle so as to rotate therewith and terminating at the other end thereof adjacent to a yarn guide, said body member having a curved inner surface formed and extending at least partially about the axis of rotation of the spindle and the yarn, as it passes from the 35 spindle to the yarn guide, bearing against said inner surface.

2. A device for limiting the size of the balloon of yarn in double-twist spindles comprising, in combination, body member having an inner 40 oval-shaped surface symmetrically located about

a longitudinal axis of the body member, said body member terminating at one end thereof adjacent to a yarn guide and being fixedly connected at its other end to the spindle so that the body member rotates with the spindle and the yarn issuing from the spindle contacts the inner oval-shaped surface of the body member so as to be guided thereby and pass from said body member to said yarn guide, and the longitudinal axis of said body member coinciding with the axis of rotation of said spindle.

3. A device for limiting the size of the balloon of yarn in double-twist spindles comprising, in combination, a substantially cylindrical hollow body member having one end closed and the other end open, said closed end being fixedly connected to the spindle so that said body member rotates therewith and the longitudinal axis of said cylindrical body member coinciding with the axis of rotation of said spindle, whereby the yarn issuing from the spindle may be guided along the inner surface of the cylindrical body member so as to thereby limit the size of the balloon of yarn.
